Renewed August 3, 1938

23 Claims. (Cl. 83—42)

This invention relates to improved means—process and apparatus—for the bleaching of flour. Its general object is to accomplish that operation in a thoroughly efficient manner, with uniformity of bleaching action throughout the mass of flour, and without injury to, or detrimental effect upon, the product, either through the over-bleaching of any part thereof, or from other causes.

10 A further object of the invention is the production of a maximum output of properly bleached flour with a minimum quantity of bleaching agent and with a minimum use of machinery, floor-space and power.

15 A further object of the invention is the avoidance of certain objections and difficulties, hereinafter described, (some of which are of a serious character) that attend the use of the processes and apparatus now commonly employed for the bleaching of flour.

20 The invention comprises a novel process and novel apparatus, by means of which the above and other desirable objects are successfully accomplished.

25 While the said process is not limited in its broad aspect to the use of any particular bleaching gas or agent, it is specially adapted for use with nitrogen trichloride, the trade name whereof is "Agene".

30 From the beginning of the art of bleaching flour by the action of a gaseous bleaching agent, effort has been made to devise means—process and apparatus—such as would insure the uniform exposure of all particles of the flour to the effective action of the said gaseous agent. It has been recognized that uniformity of bleaching effect throughout the entire mass of the flour is of the highest importance, but it has not been found possible, with the means heretofore available, to 35 attain that result commercially. On the other hand, it is highly important also, for reasons stated below, that no excess of gas be used, that no part of the flour be over-bleached, and that the apparatus be thoroughly self-cleaning.

40 Attempt has been made heretofore to accomplish the bleaching of flour commercially, with the aid of gaseous agents by subjecting the mass of flour while passing through the bleaching chamber to agitation of such sort as to convert it into a cloud of dust; the theory being that in that form the bleaching gas can diffuse itself with a proximate uniformity throughout the entire mass and thus act effectively upon every particle of the flour.

45 Machines of various types have been devised and

brought into commercial use so constructed that the flour is stirred up into a cloud and subjected, while in that condition to the action of a bleaching gas. In apparatus of this class the bleaching chamber is usually in the form of a 5 horizontally disposed cylinder or drum, within which are a series of revolving beaters, paddles, or equivalent devices, whereby the flour is whipped into a cloud, and whereby it is also propelled through the machine from the point of 10 inlet at one end to the discharge orifice at the other.

One serious drawback attending the use of machines of this type is that they are not self-cleaning; for the beaters do not come into contact 15 with the inner surface of the drum, the result being that some of the flour adheres thereto, forming a crust; and this adherent crust is quickly overbleached, eventually becoming rancid and acquiring an exceedingly obnoxious odor. It is, of 20 course, inevitable that from time to time some of this overbleached and rancid crust will be jarred loose and will be disintegrated by the action of the beaters and commingled with the fresh flour as it passes through the machine. Thus the 25 latter is more or less contaminated; and inasmuch as the full effect of the overbleaching does not develop for some little time, it often happens that the contamination of the product is not discovered at the mill and is not known until complaint 30 is received from a customer. Heavy losses often result; instances being known in which customers, finding one barrel of a shipment thus contaminated, have shipped whole car loads back to the producing mills. This is one of the reasons 35 that make uniformity of exposure of all parts of the mass of flour to the action of the bleaching gas, and the self-cleaning feature, with the avoidance of overbleaching, so highly desirable.

Furthermore, it has also been found that the 40 flour passes through a machine of the horizontal cylinder type described above too quickly for the proper absorption of just the right amount of certain kinds of bleaching gases, making it necessary to use an excess of the latter, which is undesirable for various reasons.

With the object of avoiding the objections and difficulties experienced with the above described horizontal cylinder type of bleachers, and of bringing about the theoretically correct degree 50 and duration of contact between the bleaching gas and the individual particles of the mass of flour, vertical machines have been devised. These are sometimes circular and sometimes angular in cross section. The former are equipped with a 55

plurality of revolving disks which spread the flour into a thin sheet as it passes through the machine; whereas the latter are furnished with horizontally rotating beaters that whip the flour into a cloud. But even in machines of the vertical type the adherence of particles of flour to the walls of the chamber with consequent overbleaching of the encrusted particles and contamination of the entire product, is not wholly avoided. Moreover, the flour passes through this vertical type of machine as through those of the horizontal cylinder type, with such rapidity that it does not have the time required for the proper degree and duration of contact with certain kinds of bleaching gases or agents, the result being that a considerable excess of the latter is used in order to bleach the flour to the desired degree of whiteness.

It should be observed that the rapid passage of the flour through the bleaching chamber is not objectionable when chlorine is used as the bleaching agent, since the action of that gas is almost instantaneous. The objection to the rapid transit of the flour through the machine develops when one of the more slowly acting gases (such as nitrogen trichloride) is used; the latter having come into wide use in the past few years.

It should be further observed that it is not entirely for economy's sake that the use of an excess of the bleaching gas should be avoided; for the cost of the bleaching gases or agents is relatively small. The importance of avoiding over-exposure of any part of the flour to the action of the gas is because of the effect thereof upon the flour itself. The latter is permeated with a vegetable oil in which resides a yellowish coloring matter (called "carotin" because of its resemblance to the color of the vegetable carrot) and the object and effect of the bleaching operation is to decolorize the carotin by oxidation, changing it from yellow to white. The important point then is that the action of the bleaching agent should go far enough to decolorize the carotin sufficiently but should not be allowed to go farther than necessary for the accomplishment of that object, because, if carried farther, the gas oxidizes the vegetable oil itself, producing rancidity. And, as already stated, it frequently happens that the effect of an excess of contact between the gas and the flour (or parts of the mass of the latter) does not develop to the point of a manifestation of rancidity until the lapse of a week or more. It will thus be clearly seen that, in all cases where the transit of the flour through the bleaching chamber is too rapid, it is necessary to use an excess of the bleaching gas, with the attendant danger of producing the deleterious effects described above.

According to the present invention, the flour is not converted into a cloud and exposed to the action of the bleaching gas while suspended in the air, but on the contrary is spread out into a very thin or shallow stream, and in that form is conducted slowly through the bleaching chamber. This essential part of the process may be accomplished in a variety of ways, some of which will be specifically described hereinafter.

The bleaching gas is admitted in regulated quantity at a suitable point or points so that it diffuses itself throughout the bleaching chamber; the result being that the flour, during its transit through the apparatus, is in constant contact with the gas. In determining the length of time necessary for the absorption of the proper amount of gas by the flour, the principal factors are the

height of the apparatus, the number of trays therein, and the speed at which the trays are gyrated.

While ordinarily the bleaching agent is in the form of a gas generated outside the bleaching chamber and admitted thereinto by a suitable inlet or inlets, the invention may be carried out by the use of powders which, when mixed with the flour, liberate a bleaching gas. Several powders of that character are available.

But for the full accomplishment of the objects of this invention something more is required besides causing the flour to pass through the bleaching chamber in a wide and shallow stream; namely, that the particles of the stream of flour while in transit should be constantly changing their relative positions, so that all the particles will be equally acted upon by the bleaching agent; in other words, so that the bleaching action may be uniform throughout the mass of product.

The most effective method thus far found of producing the two-fold motion referred to above—viz. (1) the slow travel of the flour through the bleaching chamber in the form of a widely spread, shallow stream, and (2) the constant shifting of the relative positions of the particles composing the stream—is by imparting to the trays, ledges, shelves or other elements over the surface of which the flour stream passes, a rapid and somewhat energetic gyratory motion.

Machines of various types capable of imparting the desired motion for other purposes (as for sifting) are already in general use, and can readily be reorganized, or, reconstructed as herein-after described, so as to be adapted for use in carrying out the present invention.

Successful results have been obtained—that is to say, a large production of flour thoroughly and uniformly bleached—by the use of an apparatus comprising stacks of trays horizontally disposed one above another, the arrangement being such that the stream of flour pursues a zig-zag course, changing the direction of its travel when it drops from one tray to the next. But the rays may be more or less inclined, either fixed in position or made adjustable to any desired angle. And instead of disposing the trays one above the other and causing the stream of flour to reverse the direction of its movement, the trays may be disposed after the manner of a spiral stairway, according to the arrangement of the sieves of the Allis-Chalmers sifter. Or the arrangement may be that of a straight stairway; or any of a number of other arrangements may be used. In fact, the process may be successfully carried out in an apparatus constructed after the general pattern of any of the well-known kinds of flour sifters now in use, each sieve being given an imperforate bottom to constitute a tray and being so formed as to spill the flour off one end onto the tray next beneath, and the apparatus being so constructed and organized that the flour traverses the surface of each of the series of gyratory elements successively.

In the accompanying drawings:

Fig. 1 is a front elevation of an apparatus that has been found suitable for use in carrying out the new process;

Fig. 2 is a top plan view of the same;

Fig. 3 is a vertical section thereof on line 70 3—3 of Fig. 1;

Fig. 4 is a top plan view of one of the trays;

Fig. 5 is a similar view showing a different form of self-cleaning devices;

Fig. 6 is a diagrammatic view in side eleva- 75

tion illustrating another form of apparatus suitable for carrying out the new process;

Fig. 7 is a horizontal section and plan on line 7-7 (Fig. 6);

5 Figs. 8, 9, and 10 illustrate still another form of apparatus that may be used in practicing the process herein described, Fig. 8 being a side elevation, Fig. 9 a vertical section on line 9-9 (Fig. 8), and Fig. 10 a horizontal section on line 10-10 (Fig. 9);

10 Fig. 11 is a vertical section, on a larger scale, of one of the trays shown in Figs. 8-10.

15 Figs. 12-15 illustrate a bleaching apparatus constructed on the plan of the Allis-Chalmers sifter, Fig. 12 being a top plan view, Fig. 13 a side elevation, Fig. 14 a partial perspective view (on an enlarged scale) showing the arrangement of the trays relative to each other, and Fig. 15 a diagrammatic view showing the paths of 20 the several flour streams.

25 The bleaching apparatus illustrated in Figs. 14, which is shown by way of example only, comprises a series of boxes or trays 15, of identical construction, square or rectangular in shape, and having a flat imperforate bottom or floor 16, the box or tray being made of wood, hard rubber, sheet metal, or other material, preferably one not affected by the corrosive action of the 30 bleaching agent.

35 At one end of each tray and extending from side to side thereof is an aperture or preferably a series of narrow apertures or slits 17, which may be formed by parallel wires set close together, between which the flour, after having traversed the floor 16 of the tray, drops to the one next beneath. The wires assist in splitting up the stream of flour as it falls between them, thus facilitating the contact of the gas with all 40 particles of the mass of flour.

45 In stacking the trays one above another they should, of course, be alternately reversed as shown in Fig. 3, so that the discharge end of each tray is directly above the imperforate end of the tray next beneath it.

50 The frame or structure by which the trays are supported, and the means whereby the required vibratory motion is imparted thereto, may be of various sorts. The structure and actuating mechanism illustrated in Figs. 1-3 are in all essential respects the same as those of a well-known flour sifting apparatus. The apparatus as shown comprises four sets A, B, C, D, of trays stacked vertically (though the number of trays may be more or less), each set being provided 55 with an inlet 18 for the flour at the top and an outlet 19 therefor at the bottom. Except for said openings each set of trays is made nearly air-tight, this being accomplished in any suitable way, as by interposition of a packing strip, of felt, rubber or other suitable material, between the top edge of each tray (to which edge said packing is preferably secured) and the bottom of the tray above.

60 The entire structure is suspended from a suitable overhead support by flexible hangers 20, which usually are rods of wood or metal; the object being to permit a certain extent of gyration in an approximately horizontal plane. This vibratory motion is commonly produced, in the 65 type of apparatus shown in Figs. 1-3, by means of a crank shaft 22, 23, journaled in a step 24, and journaled also in the top and bottom cross pieces 25, 26 of the frame. The shaft carries a counterbalance weight 27 and is driven by a belt 28 and pulley 29.

70 The gas inlets 30, which pass through the sides of the casing 17a, are preferably located nearer the top than the bottom of the apparatus, and far enough from the top to insure that no gas will escape at the flour inlet. It is easy to ascertain by experience how far below the top the gas inlets should be located.

75 In order to insure the successful bleaching of the flour, and specifically to prevent the arrest and consequent overbleaching of particles of flour aggregated in small masses, means are provided which may be designated generically as "self-cleaning" means. These may be of various sorts, preference being given to such as cause a jarring or concussion of the trays and of any surfaces with which the flour makes contact in its transit through the apparatus. As shown in Figs. 3 and 4 the self-cleaning action is effected by means of solid objects 31, one or several in each tray, and loose therein.

80 These loose solid objects are shown in Figs. 3 and 4 as spherical in form, but they may be of any suitable shape. They may be made of wood, hard rubber, or other suitable material. Their main function is to strike against the sides of the tray in which they are located and the bottom of the tray next above and by concussion to jar off any particles of flour that may tend to adhere to the walls thereof. They serve also to assist somewhat in stirring up the flour and thus bringing all particles thereof into contact with the bleaching gas.

85 It is deemed desirable as a precaution against the lodgment of flour in the corners of the trays to fill the corners with angle pieces 32.

90 The operation of the apparatus is obvious. The mass of flour entering at 18 is caused by the gyratory motion of the apparatus to spread out over the floor 16 of the uppermost tray and to traverse the same slowly; and inasmuch as all the flour that reaches the apertured part of the tray drops to the next tray beneath, the flow of the stream of flour is thereby determined toward that end. When the trays are grouped and stacked as in Figs. 1-3 the direction of the stream 95 is alternately reversed; but according to other arrangements of the trays, such as described below, the direction of the flour stream is not reversed. In the course of the slow traverse of the stream of flour from one end to the other of each tray there is, of course, a continual turning over and over of the individual particles, and a shifting of the relative positions of said particles, such as to bring them all into effective contact with the bleaching gas; the result being, as has been fully demonstrated in practice on a 100 commercial scale, that the flour issuing from the discharge orifices 19 is bleached uniformly, and bleached thoroughly without overbleaching of any part. This result is accomplished, moreover, with a minimum quantity of bleaching gas and without the danger of any particles of flour being arrested in their progress through the machine and retained therein longer than the requisite time for proper bleaching.

105 In the apparatus shown in Figs. 1-4 the trays 15 are arranged so that the plane imperforate surfaces over which the flour travels are horizontal. But in some cases it is, or may be, deemed desirable to quicken the travel of the flour stream; and for that purpose, or for other reasons, the trays may be arranged with their floors slightly inclined though still approximately horizontal. In such case the solid objects 31 of Figs. 3 and 4 if loose might not act effectively,

110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

since they would tend to gravitate to the depressed ends of the trays. Therefore, as shown in Fig. 5 the self-cleaning means may consist of the chains 33, which extend from end to end of the tray and which are attached thereto at each end, as by means of the screw eyes or staples 34. The chains are long enough to be quite slack, and to them are attached at intervals pieces of rubber or other material 49, which may be spherical 10 as in Fig. 5, or cubical as in Fig. 7. The vibratory motion of the apparatus causes these freely dangling chains to sweep over the floor of the tray and to strike forcibly the sides thereof, thus effectually preventing the adherence of particles 15 of flour to any part of the tray.

In Figs. 6 and 7 is illustrated diagrammatically another form of apparatus that is suitable for carrying out the process. The scheme of this apparatus somewhat resembles a type of flour sifter in commercial use, known as the "Rotex". In this apparatus there is no casing that encloses all of the trays, each individual tray 15 being made airtight. The several trays are inclined although as shown in Fig. 6 the inclination is 20 somewhat exaggerated, and each communicates with the one next beneath it by means of an impervious flexible tube or "stocking" 35. At its high or receiving end, each tray is supported and given a rotary vibratory movement by a crank 30 pin 36 loosely engaging an opening in a bracket arm 37 secured to the tray. At each side of the low or exit end of each tray there is a slide block 38 secured to the tray by a pivot pin 39. Each slide block works freely in a slideway or groove in 35 a support 40, whereby each tray is supported at its low end to move backward and forward with a slight sideways movement. Each stocking 35 is to be made sufficiently long and full to accommodate the difference of movement of the trays 40 at the point where they are in communication through the stocking. As shown in Fig. 7, each tray is provided with chains 33 and solid objects 49 (square blocks in this instance).

Figs. 8, 9 and 10 illustrate diagrammatically an 45 apparatus patterned after the plan of what is known as the "Plansifter" type of flour sifters. This apparatus comprises four or more sections or stacks of trays, A, B, C, D, (Fig. 8) which are arranged side by side and are supported by the 50 flexible hangers 20. The principal difference between this apparatus and that shown in Figs. 1-4 is that the more elongated trays are equipped with carrier flights 43 which are placed along the side of the trays and act as a means of propelling the flour toward the discharge end of each tray. As shown in Fig. 11, a strip of wood 45 is placed across each tray at a distance from the bottom sufficient to allow the flour to pass underneath it, the purpose of the stripes being to keep the 55 solid objects 49 properly distributed in the trays and not to allow them to collect at the discharge end of each tray where they would otherwise be propelled by the carrier flights.

Figs. 12-15 illustrate a reorganized sifter of 60 the Allis-Chalmers type. The trays 15 are of trapezoidal form, and are identical in size and shape. In the example illustrated they are arranged in three groups, though the number of the groups is variable. Each group is arranged 65 after the manner of a spiral stairway, the shorter side 51 of each tray being towards the center of the apparatus. The three spirals have a common center, and all are enclosed in an air-tight cylindrical casing 52, which is supported by flexible suspension rods 20, and gyrated by power 70

driven mechanism similar to that shown in Fig. 1.

The relative arrangement of the trays forming one of the spirals is illustrated in perspective in Fig. 14. The apertures 17 in each tray, through 5 which the flour passes to the next tray beneath, are in one of the vertical sides (that adjacent to the next tray) instead of in the bottom of the tray. These apertures may be formed by wire 10 nails properly spaced.

In the apparatus as illustrated the dimensions and proportions of the trays are such that it takes just six trays to make a complete turn of the spiral within the compass of the cylindrical casing 52. This makes it possible to have three 15 series of trays, each series constituting a complete and continuous spiral having its own independent flour inlet 18 and outlet 19. In other words, it makes possible to have three separate streams of flour flowing through the machine, each in a 20 spiral path of its own, and each making five drops to a lower level in the course of each turn of the spiral. These three separate paths are indicated diagrammatically in Fig. 15 which represents cylinder 52 as flattened out into a plane; one 25 path being represented by a solid line 54, another by dotted line 55, and the third by a dot and dash line 56.

The three inlets 18 for the respective series of trays are equidistant from each other (120 degrees apart); and of course each inlet communicates directly with the top tray of one of the series. The top tray of each series is directly above the third tray of the next series to the left (clock-wise direction) and its third tray down is 35 directly beneath the top tray of the adjacent series to the right (counter-clockwise direction). It is, of course, immaterial which direction the spirals take. The loose solid objects 31 are shown as in the form of disks.

Obviously, by appropriate alteration of sizes and proportions the cylinder could be made to accommodate two series of trays in spiral arrangement, or four, or even a larger number.

It is obvious that in certain of the forms of apparatus shown one set (or several) of the trays could have foraminous bottoms, so as to act as sieves, and thus the two operations of sifting and bleaching could be carried on simultaneously. For example, referring to Fig. 2, the 45 section D could be composed of sieves of the usual construction, while sections A, B and C could have trays such as described herein. Thus three different streams of flour, which might be each of a different grade from the others, would be 50 undergoing bleaching in sections A, B, C, while section D was operating as a sifter. This is 55 deemed to be an important practical advantage of the present invention.

In the case of a mill whose capacity is so small as not to require a complete sifter to be used for bleaching, a small bleaching apparatus may be mounted as an independent unit on top of the sifter and thus receive its required vibratory motion indirectly through the latter.

Another advantage realized by the present invention is the great saving in power and in the amount of machinery required relatively to a given output. Thus it has been found by experience that an output which formerly required sixteen agitators of the horizontal cylinder type, driven by belts aggregating eighty-two inches in width, may be (and now is) obtained by using three sections of one sifter driven by a four-inch belt. There is a corresponding saving in the 70 75

number of "controls" which are supplied by the manufacturers of the bleaching apparatus for metering the gas supplied to the bleaching apparatus; and there is also a corresponding saving 5 in floor space in the mill.

What is claimed is:

1. A process of bleaching flour which includes delivering the flour onto an approximately horizontal plane imperforate surface; imparting to 10 said surface approximately horizontal gyratory movement such as to cause the flour to be spread upon and to travel over and off said surface with simultaneous shifting of the flour particles relative to each other during said travel; confining the flour to said surface during its travel there- 15 over; and bringing a bleaching agent into contact with the flour while it is traversing said surface.

2. A process of bleaching flour which includes 20 delivering the flour onto the uppermost of a plurality of approximately horizontal plane imperforate surfaces arranged at descending levels; imparting to said surfaces approximately horizontal gyratory movement such as to cause the 25 flour to be spread upon and to travel over and off each surface with simultaneous shifting of the flour particles relative to each other and to fall from each upper surface onto a lower surface; and bringing a bleaching agent into contact with 30 the flour while it is traversing said surfaces.

3. A process of bleaching flour which includes 35 delivering the flour onto an approximately horizontal plane imperforate surface imparting to said surface approximately horizontal gyratory movement such as to cause the flour to be spread upon and to travel over and off said surface with simultaneous shifting of the flour particles relative to each other during said travel; confining the flour to said surface during its travel there- 40 over bringing a bleaching agent into contact with the flour while it is traversing said surface; and repeatedly jarring said plane imperforate surface.

4. A process of bleaching flour which includes 45 delivering the flour onto the uppermost of a plurality of approximately horizontal plane imperforate surfaces arranged at descending levels imparting to said surfaces approximately horizontal gyratory movement such as to cause the 50 flour to be spread upon and to travel over and off each surface with simultaneous shifting of the flour particles relative to each other and to fall from each upper surface onto a lower surface; confining the flour to said surfaces during 55 its travel thereover; and bringing a bleaching agent into contact with the flour while it is traversing said surfaces.

5. The process as specified in claim 4 with the further step of repeatedly jarring said plane imperforate surfaces.

6. A process of bleaching flour which includes 60 delivering the flour onto the uppermost of a plurality of approximately horizontal plane imperforate surfaces arranged at descending levels in an enclosure; imparting to said surfaces approximately horizontal gyratory movement such as to cause the flour to be spread upon and to travel over and off each surface with simultaneous shifting of flour particles relative to each other and to fall from each upper surface onto a lower surface; confining the flour to said surfaces during 65 its travel thereover; introducing a bleaching agent into said enclosure and into contact with the flour while it is traversing said surfaces; and

repeatedly jarring said plane imperforate surfaces.

7. A process of bleaching flour which includes 5 delivering the flour onto the uppermost of a plurality of approximately horizontal plane imperforate surfaces arranged at descending levels in an enclosure; imparting to said surfaces approximately horizontal gyratory movement such as to cause the flour to be spread upon and to travel over and off each surface with simultaneous shifting of flour particles relative to each other and to fall from each upper surface onto a lower surface; and introducing a bleaching agent into 10 said enclosure and into contact with the flour while it is traversing said surfaces.

8. The process specified in claim 2, with the further step of repeatedly jarring the surfaces over which the flour travels.

9. The process specified in claim 7, with the further step of repeatedly jarring the surfaces 20 over which the flour travels.

10. Apparatus for treating flour with a bleaching agent said apparatus having openings for the inlet of flour and bleaching agent and for the outlet of flour and including in combination a tray 25 through which the flour passes in travelling from said flour inlet to said flour outlet, said tray having an imperforate plane inner bottom surface approximately surrounded by an upright rim or flange constituting a part of the tray; means for supporting the tray with its said bottom surface approximately horizontal; means for imparting approximately horizontal gyratory movement to said tray and means for confining the bleaching agent to the zone of treatment, said zone comprising the path traversed by the flour in passing 30 through the tray.

11. The combination as specified in claim 10, with the addition of means freely movable in the tray for imparting thereto repeated jars or 40 concussions.

12. An apparatus for treating flour with bleaching agent having in combination openings for the inlet of flour and bleaching agent and for the outlet of flour; a plurality of trays 45 through which the flour passes in travelling from said flour inlet to said flour outlet, each tray having an imperforate plane inner bottom surface; means for supporting said trays at different levels each with its said bottom surface approximately horizontal and with the trays in such relation that each upper tray delivers flour through an exit opening thereof to a lower tray; and means for imparting approximately horizontal 50 gyratory movement to said trays.

13. The combination as specified in claim 12, with the addition of means freely movable in the trays for imparting thereto repeated jars or concussions.

14. An apparatus for bleaching flour having 60 in combination openings for the inlet of flour and bleaching agent and for the outlet of flour; a plurality of trays through which the flour passes in succession in travelling from said flour inlet to said flour outlet, each tray having an 65 imperforate plane inner bottom surface; means for supporting said trays at different levels with the bottom surface of each approximately horizontal and with the trays in such relation that each upper tray delivers flour through an exit 70 opening thereof to the next lower tray; and means for imparting approximately horizontal gyratory movement to said trays.

15. The combination specified in claim 14, with the addition of means freely movable in 75

the trays for imparting thereto repeated jars or concussions.

16. An apparatus for bleaching flour having in combination an enclosing casing supported for 5 gyratory movement and having openings for the inlet of flour and bleaching agent and for the outlet of flour; a plurality of trays positioned one above another in said casing through which trays the flour passes in succession in travelling 10 from said flour inlet to said flour outlet, each tray having an imperforate plane inner bottom surface over which the flour travels and each upper tray delivering flour through an exit opening thereof to the next lower tray; means freely 15 movable in one or more of said trays for imparting thereto repeated jars or concussions; and means for imparting approximately horizontal gyratory movement to said casing and the trays therein.
17. An apparatus for treating flour with bleaching agent said apparatus having openings for the inlet of flour and bleaching agent and for the outlet of flour and including in combination, 20 a plurality of trays through which the flour passes in travelling from said flour inlet to said flour outlet, each tray having an imperforate plane inner bottom surface approximately surrounded by an upright rim or flange fixed to said surface; means for supporting said trays at different levels each with its said bottom surface approximately horizontal and with the trays in 25 such relation that each upper tray delivers flour through an exit opening thereof to a lower tray; means for imparting approximately horizontal gyratory movement to said trays and means for confining the bleaching agent to the zones of treatment, said zones comprising the path traversed by the flour in passing through the trays.
18. The combination specified in claim 17, with 30 the addition of means for repeatedly jarring said trays.

19. Apparatus for treating flour with a bleaching agent having in combination a casing having openings for the inlet of flour and bleaching

agent and for the outlet of flour; a tray through which the flour passes in travelling from said flour inlet to said flour outlet, said tray having an imperforate plane inner bottom surface approximately surrounded by an upright rim or flange and also having a discharge opening through which flour passes from said inner bottom surface; means for supporting the tray with its said bottom surface approximately horizontal; and means for imparting approximately horizontal gyratory movement to said tray.

20. The combination specified in claim 19, with the addition of means for repeatedly jarring the surface over which the flour travels.

21. An apparatus for treating flour comprising 15 an enclosure, a series of removable imperforate trays at different levels therein, each tray communicating by suitable outlet with the next one beneath it in the series, said trays being arranged in the form of a spiral stairway, said apparatus 20 having flexible supporting means and power means for imparting vibratory motion thereto.

22. An apparatus for treating flour comprising 25 an enclosure, a series of removable imperforate trays of trapezoidal form at different levels therein, each tray communicating by suitable outlet with the next one beneath it in the series, said trays being arranged in the form of a spiral stairway, said apparatus having flexible supporting means and power means for imparting vibratory motion thereto.

23. An apparatus for treating flour comprising 30 an enclosure, a plurality of series of imperforate trays at different levels, each series of trays having an independent flour inlet and flour outlet 35 so as to constitute a continuous passageway for a stream of flour through said apparatus, each individual tray communicating by suitable outlet with the next adjacent one in the same series, each series of trays being arranged in the form 40 of a spiral stairway, flexible supporting means for said apparatus, and power means for imparting vibratory motion thereto.

CAMPBELL HOUK SMITH.
